UNITED STATES PATENT OFFICE.

LANDON C. MANNING, OF NEW YORK, N. Y.

DESIGN FOR A ROOF FOR A VENDING-MACHINE CASING.

Application filed June 28, 1926. Serial No. 18,203. Term of patent 3½ years.

To all whom it may concern:

Be it known that I, LANDON C. MANNING, a citizen of the United States of America, and a resident of the city, county, and State of New York, have invented a new, original, and ornamental Design for Roof for Vending-Machine Casing, of which the following is a specification, reference being had to the accompanying drawing, forming a part thereof.

In the drawing the Figure 1 represents a view in front elevation of a roof for vending machine casing and Figure 2 is a plan view of the same showing my new design.

I claim:

The ornamental design for a roof for a vending machine casing as shown.

LANDON C. MANNING.
